ARTHUR H. SYMONS, OF KANSAS CITY, KANSAS.

CLAMP FOR CONCRETE-FORMS.

1,020,164.

Specification of Letters Patent. Patented Mar. 12, 1912.

Application filed February 16, 1911. Serial No. 609,330.

To all whom it may concern:

Be it known that I, ARTHUR H. SYMONS, a citizen of the United States, residing at Kansas City, in the county of Wyandotte 5 and State of Kansas, have invented certain new and useful Improvements in Clamps for Concrete-Forms; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

My invention relates to a clamp for concrete forms and more particularly to a device for supporting and holding together a form for molding girders in the construction 20 of a concrete building.

It is the principal object of my invention to provide a device of this character which will act as a hanger as well as a clamp and will serve to support the girder form, so 25 that the usual intermediate and temporary supports for such forms need not be used. In accomplishing this object I have provided the improved details of structure which will presently be fully described and are illustrated in the accompanying drawings, 30 wherein:—

Figure I is a perspective view of a clamp constructed according to my invention; Fig. II is a perspective view of a girder form 35 equipped with one of the clamps. Fig. III is a detail view of a tightening tool used with the clamp.

Referring more in detail to the parts:— 1 designates hanger members which are 40 preferably formed of stiff strap metal and are provided at their upper ends with in-turned ears 2, the latter being preferably formed of cast metal and riveted to the ends of the hangers. The lower ends of the 45 hanger members are provided with apertures 3 for receiving the pins 4.

5 designates a base bar which is preferably formed of two pieces 6, of stiff strap metal, spaced at their central portion by a 50 bar 7 to provide the end slots 8, and having registering apertures 6' in their free ends. The bar 7 is preferably slightly less in length than the width of an ordinary girder form, so that when the device is in use the 55 hanger bars 1 may project through the end slots 8 and be tightened against the form,

without being limited by the spacer. Pivotally connected with the hanger bars, near their upper ends are the levers 9 comprising the bell cranked bars 10 which overlie the hanger bars and are connected therewith by the pins 11. Pivotally connected with the levers 9, near their connection with the hanger bars, by the pins 13, are the arms 14 which are adapted for projection between the base members 6 and are provided with the apertures 15.

16 designates yokes which are pivotally connected with the arms 14 by means of pins 17 which extend through the yoke arms and through apertures 15 in the lever arms, each of the yokes being constructed to provide a space 18 through which the ends of the base 5 may move freely under certain conditions. Under other conditions, the heads 19 of said 75 yokes may be turned to bring their edges into clamping contact with the lower edges of the base members, so that the yokes will hold against the arms to enable the clamp to be set, as will presently be described.

20 designates bolts which extend through the yoke arms in position to be engaged by the upper edge of the base 5 and provide clamping surfaces for the upper edge of the base, so that the holding action may take 80 place.

21 designates a girder form, which is supported in its proper position by cross brackets 22' on pillars 22, so that such side members may support a substantial weight, such 90 cross brackets being preferably nailed to the wooden form within which the pillar is cast. In the upper edge of the top boards of the girder form are notches 23, which are adapted for receiving the clamp ears 2, as illustrated in Fig. II; there being a desired number of said notches throughout the length of the girder for accommodating any sufficient number of clamps to properly support the girder form and the material which is 100 poured thereinto.

24 designates a tool for tightening the base bar against the form, which comprises the flat handle part having a cam head 25 and laterally projecting pins 26.

In using my device, the girder form is fixed to the columns and the clamps hung from the upper form members, as illustrated in Fig. II. To set the clamps, it is preferable to first suspend the hanger bars from 110 the form notches and move the base bar into position thereover, the pins 4 being projected

through apertures in the lower ends of the hanger bars when the base has been moved tightly against the bottom of the form, so as to hold the parts together and support 5 the base. The hanger bars are then moved close again at the sides of the form and pins 4' projected through apertures 6' in the ends of the base, so as to hold the hanger bars in place. The yokes 16 are then fitted 10 over the ends of the base and inwardly to about the angle shown, so that the edge of the yoke head will bite against the under edge of the base. When the parts are so arranged, the levers 9 will be in their released 15 position (dotted lines Fig. I). When it is desired to close the form for pouring, the pin 26 of the lever 24 is placed in one of the apertures 3 in the hanger bars 1 and the cam head of the lever moved against the bottom 20 of the base bar so that the bar is moved into close contact with the bottom of the form and a pull exerted on the hanger. When the parts have been so tightened, a pin 4 is placed in one of the apertures 3 to support 25 the base in its tightened position. The levers 9 are then lowered to their clamping position, thereby exerting a leverage on the hanger bars, which tends to move same inwardly into close contact with the form 30 sides. With a girder form provided with a number of clamps of this character, the form may be closed tightly throughout its length to form a compact, close structure, so that when the side members of the former, are 35 properly secured to the columns, the form may be supported without the aid of the usual temporary columns, thereby effecting a saving of labor and material in the erection of such structure. It is apparent that 40 a number of these clamps will be required for the construction of each form, but as the operation and arrangement of the clamps is identical, I have illustrated but one, in the figure illustrating the clamp in combination 45 with a form. To remove the girder form, the levers 9 are released and the pins 4-4' removed to enable the clamp members to spread so that they may be removed from the form. The form itself may then be 50 taken down and may be used again in a different place.

It is apparent that the operations of erecting and taking down the form may be easily and quickly performed and that material of 55 which the form is constructed will be damaged but slightly, if at all, in either operation.

Having thus described my invention, what I claim as new therein and desire to secure 60 by Letters-Patent is:—

1. A clamp for concrete forms comprising hanger bars having ears at their upper ends

for supporting said clamp from above, a two piece base bar carried by the hanger bars and having end portions projecting beyond the 65 hangers, and tightening levers pivotally mounted on the hangers and adapted for adjustable connection with the base bar.

2. A clamp for concrete forms comprising hanger bars having ears at their upper ends 70 for supporting said clamp from above and having apertures in their lower ends, a base bar having split ends through which the hanger bars are projected and provided with apertures, pins projecting through apertures 75 in the hanger bars to support the base bar, and pins projecting through apertures in the base bar to keep the hanger bars.

3. A clamp for concrete forms comprising hanger bars having ears at their upper ends 80 for supporting said clamp from above and having apertures in their lower ends, a base bar having split ends through which the hanger bars are projected and provided with apertures, pins projecting through apertures 85 in the hanger bars to support the base bar, pins projecting through apertures in the base bar to keep the hanger bars, and levers for tightening the hanger bars against a 90 form.

4. The combination with adjustable hanger and base bars, of tightening levers comprising levers pivotally connected with the hanger bars, yokes slidably mounted on the base bars, and arms having pivotal connection with the levers and yokes, substantially as and for the purpose set forth. 95

5. A clamp for concrete forms comprising hanger bars, a base bar, levers pivotally connected with said hanger bars, arms pivotally connected with said levers, each arm being provided with a plurality of apertures, and yokes adapted for supporting said base bar each of said yokes having a pin pivotally projected therethrough and 100 through an aperture in one of the lever arms. 105

6. A clamp for concrete forms comprising hanger bars, a base bar, a lever pivotally connected with each hanger bar, an arm pivotally connected with each lever, a yoke pivotally connected with each of said arms and inclosing a portion of the base bar, and a bolt extending through each yoke and limiting the open space between the members of said yoke, substantially as and for the purpose set forth. 110 115

In testimony whereof I affix my signature in presence of two witnesses.

ARTHUR H. SYMONS.
